EMERY R. GARD, OF CHICAGO, ILLINOIS.

Letters Patent No. 65,069, dated May 28, 1867.

IMPROVED BRICK-PRESS.

The Schedule referred to in these Letters Patent and making part of the same.

TO ALL WHOM IT MAY CONCERN:

Be it known that I, EMERY R. GARD, of Chicago, in the county of Cook, and State of Illinois, have invented an improved Brick-Press; and I do hereby declare that the following is a full and exact description thereof, reference being had to the accompanying drawings, making part of this specification—

Figure 1 being a top view of the press.

Figure 2, a rear elevation thereof.

Figure 3, a central vertical section of the mould-wheel track and adjacent parts.

Figure 4, a side view of one of the mould-followers.

Figure 5, a transverse vertical section of the follower.

Figure 6, a transverse vertical section of the pressure-bar or bearing, and adjacent parts.

Figure 7, a transverse vertical section of one of the mould-lids.

Figure 8, a vertical section of the bearing-box of the mould-wheel friction-roller.

Figure 9, a horizontal section of a follower of improved construction.

Like letters designate corresponding parts in all of the figures.

My improved brick-press is of that class which has a horizontal revolving mould-wheel, B, provided with concentric mould-mortises extending through its entire thickness, and followers, S S, sliding up and down therein, the said followers riding upon a circular or annular track, F. These general parts require no description, except in particulars of improvement which I have made upon them. The whole machinery is mounted in a suitable frame, A, of no peculiar construction. The revolving mould-wheel B is secured to a vertical shaft, C, to the top of which horse, steam, or water-power is applied, the crank D representing in general any means of communicating the power to the machine. Each follower has a roller, U, which carries it on the track F, being rounded somewhat in the middle, so as to bear centrally on said track, and, to render the track more firm and durable, the central part thereof, on which the rollers bear, or a portion of the same where the most strain comes, is chilled or faced with steel. The portion G of the track on which the followers travel while the pressure is applying is not only adjustable up and down, but is made yielding and elastic by means of India-rubber springs H H, or their equivalent, on which the said adjustable part of the track rests. The arrangement shown in fig. 2 is suitable for applying the adjustment and the spring or springs. Two screw-bolts I I compose the bearings for the track-block G, and they have nuts g g, which serve for the adjustment. These nuts bear on washers h h, and the latter on the India-rubber springs, which rest on a beam of the frame. Nuts i i under the beam serve to keep the bolts I I in place, and to determine the degree of compression given to the India-rubber spring. Any other suitable kind or arrangement of springs may be substituted for that specified. The track-block is suitably held and guided in the framework of the machine. There are two flanges or lips, f f, projecting from the upper edge of the track F, one outside, and the other inside thereof. These flanges extend the whole circumference of the track, or nearly so, having only some part omitted to allow the withdrawal and insertion of the followers S S through the moulds. Under these flanges travel respectively two friction-rollers u u, pivoted to two downward projections of each follower S, substantially as shown in figs. 3 and 4. These rollers and track flanges not only serve to draw the followers down into the moulds, after the same are raised to expel the pressed bricks, but serve at all times to keep the followers in their proper positions in the moulds. The rollers, used instead of hooks, scarcely add to the friction of the machine, as ordinarily they are either not at all or only slightly in contact with the flanges. They are of especial advantage, in addition to their use in drawing the followers down into the moulds, for preventing the drawing out of the followers when the bricks are tilted therefrom upon their edges. In drawing the followers down into the moulds, the lids thereof are closed by the edges of the moulds, and these friction-rollers render this work easy. Thus, all danger of breaking off the lids, from not being closed, is obviated. These flanges for the track throughout its extent add to the bearing surface thereof, and to its strength. The roller U has its journals w w in removable bearing-blocks V V, which are readily taken out and reinserted sidewise in the follower, as indicated in figs. 3, 4, and 5. They are held in place by pins or bolts e e. The bearing-blocks are hollow, or have oil-cavities in them, as seen in fig. 3; and these cavities are filled with cotton or other suitable fibrous or spongy material, for absorbing the oil and supplying it constantly, by capillary action, to the journals of the roller. The oil is

introduced into the cavities through holes $o o$ from the top of the follower. Thus, the rollers are kept lubricated for a long time without the trouble of frequently taking out the followers from the machine for that purpose. I have an improved construction of the follower S , as represented in fig. 3 at the left hand, and in fig. 9. There is a lid or cap, X , placed upon the top W of the follower, there being washers $x x$, say at each corner, as in fig. 9, between the cap and top, of variable thickness and number, so as to adjust the thickness of the brick without altering the track below, and also to make and keep the lower surface of the bricks at right angles to their edges, and all their parts of even thickness. The lid or cap may be held in place by a single screw, e , in the centre, and the washers may be kept in place by pins passing through them, as seen in fig. 9. The lid, as here shown, does not turn up, but a lid for that purpose may be attached above the adjustable top. I cover the lids or tops of the followers with buckskin, or other porous leather. I find that this makes a good surface to prevent adhesion of the clay, and to allow the air to escape from under the bricks when placed in the mould. The moulds are covered with hinged lids $P P$ before applying the pressure. There are friction-rollers $p p$ in the tops of the lids to diminish the friction when the lids pass under the pressure-bar or bearing M . To each lid is attached a double-armed cam, R , the lower arm r of which strikes a projection, O , on the frame, for turning down the lids before they pass under the pressure-beam, and the upper arm s thereof strikes another stop or projection, Q , on the other side of the frame to raise the lids after passing under the pressure-bearing, and before the bricks are raised from the moulds.

The pressure-bearing M holds the lids firmly down upon the mould-wheel while the pressure is applied to the followers below by the pressure portion G of the track. The pressure-bearing M is adjusted by a screw, d , and wheel, N , and secured by a key, m , as shown in figs. 1, 2, and 6. The follower lids are raised to turn the bricks upon edge by sliding pins $y y$ in the respective followers, which are raised at the proper time by a cam, T , fig. 3, inside the track F , and thus push the lids upward, as indicated in fig. 5. At the point where the extreme pressure is given to the bricks it is desirable, if not necessary, to firmly support the mould-wheel B so that it will not yield. In order to do this, and at the same time to avoid undue friction, I employ a supporting roller, L , just opposite to the point of extreme pressure, substantially as represented. And in order to give as much extent of bearing as may be upon this roller, I form a projecting rim, b , on the lower edge of the mould-wheel. This rim may be of ogee form, as indicated, or other form convenient. In the bearing-block of this roller there is an oil-cavity, Y , fig. 8, of any form or position, below or near the journal l of the roller, and a passage, k , leads down through the cap K of the block thereto for admitting oil into the cavity. There is a cotton wick or cotton fibre, or equivalent substance, reaching up from the oil-cavity to the journal to keep it lubricated for a long time, without renewal or waste of oil, and requiring attention only at long intervals.

What I claim as my invention, and desire to secure by Letters Patent, is—

1. A follower S , provided with one or more rollers $u u$ running under and in combination with flanges ff projecting from the track nearly along its entire length, substantially as and for the purposes herein specified.
2. I also claim the removable journals $V V$ for the supporting roller U of each follower, the said bearings being provided with oil-cavities for containing oil and some porous or capillary substance to keep the journals constantly lubricated, substantially as herein set forth.
3. I also claim an adjustable top or lid, X , for the followers by means of the washers $x x$, or any equivalent thereof, for the purposes herein described.
4. I also claim the combination of the projecting rim b of the mould-wheel and the supporting roller L , for the purpose set forth.
5. I also claim the self-lubricating journal-box of the roller L , constructed substantially as herein specified.
6. I also claim the adjustable pressure portion G of the track, when combined with India-rubber or equivalent springs $H H$, substantially as and for the purpose herein specified.

The above specification of my improved brick-press signed by me this 29th day of January, 1867.
